UNITED STATES PATENT OFFICE

KARL M. HAMILTON, OF CHICAGO, ILLINOIS, ASSIGNOR TO THE BETTENDORF COMPANY, OF BETTENDORF, IOWA, A CORPORATION OF IOWA

CAR TRUCK

Application filed November 27, 1929. Serial No. 410,055.

My invention relates to improvements on car trucks, and more particularly to car trucks of the swing motion type.

An object of my invention is to provide an efficient, strong and durable swing motion truck wherein the spring plank consists of a casting supported from the transom by swing links to provide for lateral or side motion, and having integral spring seats and trunnions formed at its ends for pivotal connection with the swing links.

Another object of the invention is to provide an improved spring plank, with which is combined the spring seats and trunnion bearings in one single unit capable of being cast as a single piece, thereby eliminating the handling and assembling of numerous parts, and reducing the cost of manufacture.

Other objects of my invention will appear hereinafter.

In the accompanying drawings,

Fig. 1 is a vertical transverse section through one side portion of a car truck embodying my invention;

Fig. 2 is a vertical section, substantially on the line 2—2 of Fig. 1;

Fig. 3 is a top plan view of one end portion of the spring plank unit casting; and

Fig. 4 is a perspective view of the portion 30 of the spring plank unit shown in Fig. 3.

I have not deemed it necessary to illustrate in the drawings a complete truck, inasmuch as the invention will be apparent from the parts shown. It is understood that the other side 35 of the truck is similar to that shown in the drawings.

The truck shown in the drawings comprises, in general, the side frame A, transom B, bolster C, elliptic springs D, and the 40 spring plank E.

The side frame may be of the standard cast type having an integral upper arch bar 10 and a lower arch bar 11 of channeled or U-shaped construction, and having vertically 45 disposed guide columns 13 spaced apart to form, in conjunction with the upper and lower arch bars, a substantially rectangular opening within which the hollow ends of the transom B are positioned.

50 The transom casting comprises two sub-

stantially horizontally disposed channeled beams 12 which extend from side frame to side frame of the truck. These beams are spaced apart and are substantially parallel at their end portions. The end frame sections of the transom are integrally formed at the ends of the beams and comprise the top cross connecting member 14, bottom cross connecting member 15, and the two upright side members 16. The bottom member 15 rests 60 upon the upper surface 17 of the lower arch bar, and has, Fig. 1, a hollow boss 18 which extends down between the flanges of the lower arch bar to interlock the side frame and transom against displacement. The relative 65 height of the window opening and side frame, and the rectangular end section of the transom is such that the end frame can be inserted into the window opening and then dropped down to interlock the boss 18 with 70 the lower arch bar.

The bolster C may be of any suitable type for use in connection with lateral motion trucks. The bolster is positioned between the transom beams. The ends of the bolster bear upon the upper members of the full elliptic springs D which extend transverse to the plane of the side frames, the springs extending through the hollow end frame sections of the transom and beyond the side frames. The 75 ends of the bolster have downwardly extending lugs 22 which straddle the spring and prevent relative displacement of the spring and bolster, the lugs being spaced apart to accommodate the spring band 24 which binds 80 the leaves of the spring together.

The spring plank E extends transversely of the truck beneath the transom and bolster, and is suspended at its ends from the transom by means of the parallel suspension links 25. A pair of these links are provided at each end of the structure and the links are disposed at the sides of the spring plank. The upper ends of the links pass upwardly through suitable slots or openings 26 in the transom beams and are pivotally connected to the transom beams by the pivot pins 27 resting in suitable bearings formed in the transom beams.

The spring plank E is in the form of an integral body casting 30 having integral up- 100

standing flanges 31 at its edges to form a channel construction. At its end portions, the spring plank has three depending cross ribs 32 parallelly disposed transversely of the body portion and formed integrally with the body casting. The end portions 33 of the two outer ribs extend beyond the width of the body casting and are brought upwardly to form diagonal braces merging with the side flanges of the casting. The intermediate rib terminates flush with the side flanges so as not to interfere with the lower ends of the suspension links. The end portions 34 of the side flanges 31 are thickened where they merge with the rib braces 33 to strengthen the structure at these points and to provide a substantial connection for the lugs 35 which are positioned between the rib braces 33. The trunnion lugs are integral with the thickened portions 34 of the side flanges and are axially aligned with each other transversely of the plank. They project outwardly from the thickened portions 34 and are preferably substantially round in cross section, except their outer end portions, which are elongated vertically to form flange heads 36 which prevent the suspension links from becoming displaced or disconnected from the trunnion lugs. The lower ends of the suspension links have elongated slots 37 corresponding to the shape of the flange heads 36, so that in assembling the structure the flange heads are passed through the slots in the links and the plank then dropped downwardly until the lugs rest in the lower ends of said slots. The upper surfaces 38 of the end portions of the plank between the thickened portions of the flanges serve as spring seats for supporting the lower sections of the spring members. Since the space between the side flanges 31 of the plank is wider than the springs, this space at the spring seat portion is narrowed to the width of the springs by instanding integral lugs 39 which engage the side edges of the spring sections and prevent relative rotation of the springs and plank. These lugs are spaced apart to form the recesses 40 which accommodate the spring bands 41. Variations in height of the springs, occasioned by set in the springs or by variations in the manufacture of the parts, may be readily compensated for by the use of shims interposed between the spring bands and the spring seat surfaces 38. These shims 42 may be in the form of flat plates of suitable thickness, such as illustrated in Fig. 1, and are placed with their ends in the recesses 40 to prevent their displacement. I am aware that changes in the construction and arrangement of the parts may be made without departing from the spirit of the invention, and I hereby reserve the right to make such changes as fairly fall within the scope of the appended claims.

I claim:

1. In a car truck, the combination of a transom, suspension members mounted on said transom, a spring plank beneath the transom having laterally extending integral trunnion lugs supported in said suspension members, and means for holding said suspension members in detachable relation to said lugs.
2. A spring plank for car trucks, comprising a body casting having upstanding angular flanges adjacent its end to define a spring seat therebetween, and integral trunnion lugs axially aligned and outstanding from said flanges.
3. A spring plank for car trucks, comprising a body casting having upstanding flanges adjacent its end to form a spring seat therebetween, integral trunnion lugs axially aligned and outstanding from said flanges, and instanding lugs on said flanges above the body casting, to retain a spring on said spring seat.
4. A spring plank for car trucks, comprising a body casting having upstanding flanges adjacent its end to form a spring seat therebetween, integral trunnion lugs axially aligned and outstanding from said flanges, and integral cross ribs on said body casting.
5. A spring plank for car trucks, comprising a channeled body casting, integral outstanding trunnion lugs on its side edges adjacent its end, and having elongated heads extending transversely to the axis of said lugs.
6. A spring plank for car trucks, comprising a body casting having integral upstanding flanges to provide a spring seat therebetween on the upper side of said body, integral instanding lugs on said flanges for interlocking engagement with a spring member, integral parallel cross ribs on the under side of said body portion and extending up along the outside of said flanges, and integral trunnion lugs projecting outwardly from said flanges between said ribs.
7. A one-piece spring plank structure for railway trucks, a body portion having upstanding flanges at its sides adjacent its ends and instanding lugs spaced apart on said flanges to define a spring seat, and transverse reinforcing elements on its under side and integrally connected with said flanges.
8. A one-piece spring plank structure for railway trucks, a body portion having upstanding flanges at its sides adjacent its ends and instanding lugs spaced apart on said flanges to define a spring seat, transverse reinforcing elements on its under side and integrally connected with said flanges, and trunnion lugs integrally connected with and extending outwardly from said flanges.
9. An integral one-piece spring plank structure for railway trucks comprising a body plate having upstanding integral

flanges at its sides adjacent its ends and spaced instanding lugs on said flanges above said body to define a spring retaining seat, integral transverse ribs extending beneath the body and upwardly into merging relation with said flanges, and integral outstanding trunnion lugs on said flanges positioned between said ribs.

5 In witness that I claim the foregoing I have hereunto subscribed my name this 2nd day of November, 1929.

10 KARL M. HAMILTON.
